HAIR-DRYING IMPLEMENT

Lawrence I. Freedman, Wilmington, Del., John W. Tone, Zbleys Corner, Pa., and Seymour Rappoport, Rumson, N.J., assignors to Ronson Corporation of Delaware, Wilmington, Del., a corporation of Delaware

Filed May 3, 1960, Ser. No. 60,426

Term of patent 14 years

(Cl. D86—10)

Fig. 1.

Fig. 2.

Fig. 3.

Fig. 4.

Fig. 6.

Fig. 5.

FIG. 1 is a top plan view of a hair-drying implement showing our new design;

FIG. 2 is a side elevational view thereof as it appears with a comb attached therein;

FIG. 3 is a bottom plan view thereof as it appears with a brush attached therein;

FIG. 4 is an end elevational view as seen from the left of FIG. 2;

FIG. 5 is an end elevational view as seen from the right of FIG. 2; and

FIG. 6 is an end elevational view as seen from the left of FIG. 3 and rotated 180°.

We claim:

The ornamental design for a hair-drying implement, substantially as shown and described.
